DEEP WELL DRILLING APPARATUS

James W. Menhall, Centralia, Ill.

Application March 17, 1941, Serial No. 383,765

3 Claims. (Cl. 255—4)

This invention relates to drilling apparatus for deep bores, such as oil wells, and its object is to increase the efficiency of the drill in its regular work, and to provide certain convenience of operation under special circumstances. The apparatus includes hydraulic means for driving the drill bit while the drill pipe itself is maintained in substantially stationary relation, but in addition to the rotary power for turning the drill the present invention provides means for automatically adding intermittent hammer blows in axial direction to render the drill more effective, particularly when working in rock or other hard formations. Another object of the invention is to provide a positive clutch device by which the drill may be rotated by rotation of the drill pipe itself when desired. The invention consists in certain features and elements of construction in combination, as hereinafter described and as indicated by the claims.

In the drawings:

Fig. 1 is a vertical axial section showing a casing and rotary driving means attached to the lower end of the drill pipe but with the drill itself omitted from the extreme lower end of said casing.

Fig. 2 is a top plan view of the turbine rotor element shown on a larger scale than Fig. 1 and taken substantially at the plane indicated at line 2—2 on Fig. 1.

Fig. 3 is a detail side elevation of the turbine rotor taken partly in section at the line 3—3 on Fig. 2.

Fig. 4 is a vertical sectional view on a larger scale than Fig. 1 showing the drill bit and special actuating means associated therewith embodying this invention; section is taken as indicated at line 4—4 on Fig. 5.

Fig. 5 is a transverse section taken as indicated at line 5—5 on Fig. 4.

As shown in the drawings the drill pipe 1 is connected at its lower end with a casing 2 secured rigidly to the pipe so that if the upper end of the pipe at the mouth of the well is held against rotation, the casing 2 will also be thus anchored. The upper end of the pipe includes a fitting, not shown, connected with a suitable pumping apparatus by which a fluid commonly referred to as "mud" is pumped down the pipe 1 for actuating a hydraulic turbine device by which the drill bit is rotated. Within the upper portion of the casing 2 a centrally disposed sleeve 4 transfers the fluid to the upper end of the hollow shaft 5 from which it passes by ports 5^a into the annular space within the casing 2 and

around the drill shaft 5. This shaft carries one or more turbine rotors 6, each disposed between a pair of stator elements 7, 7, the stators having a plurality of ports 7^a each substantially parallel to the axis of the apparatus while the correspondingly spaced ports 6^a of the rotor are each slightly oblique to a transaxial plane so that the flow of driving fluid through the ports 6^a causes rotation of the shaft 5 in a well understood manner. The lower end of the shaft has a hollow bore 5^b into which the fluid passes from the last or lowest turbine element by way of ports 5^c, and the drill bit 8, secured to the lower end of the shaft 5, has a communicating central bore 15^a through which the fluid escapes for return upwardly through the well, the casing 2 of the drilling apparatus being somewhat smaller than the bore which the drill bit produces.

When the bit is thus hydraulically operated 20 it turns in the lower end of the casing 2. The bit includes a head 18 which is shown as detachably screwed into a terminal 19 carried by the end of the shaft 5, and this terminal 19 is a cylindrical member in which a plurality of drills or cutters is slidably mounted, as shown in Figure 4. Each drill includes a shank 20 with a flared lower end 21 provided with four cutting edges 22. Each of the drill shanks 20 is yieldingly upheld by a spring 24 reacting against a 25 head sleeve 25 which is screwed onto the upper end of the shank 20. The cylindrical body 19 is connected with a turbine rotor such as that shown at 6 in Figure 1, by means of a shaft 15, and the stationary bushing 16^x, in which the lower end of the shaft rotates, is fitted with a plurality of plungers 30 pocketed in the bushing and each provided with its own spring 31, tending to urge it downwardly toward the rotating body 19. The upper end of the body 19 carries sloping 30 cams 32 disposed at the same radial distance from the axis of rotation as the plungers 30, so that as the body 19 rotates, the plungers 30 ride up the inclined faces of the cams 32 and are thus lifted in opposition to their springs 31 until the 35 abrupt vertical faces of the cams pass under the plungers, allowing them to drop suddenly onto the upper ends 23^x of the drill shanks. Thus each plunger delivers a hammer blow to one of the drills, forcing the latter downwardly in opposition to its own spring 24 for attacking the 40 rock or shale through which the well is being drilled. The abrupt face of each cam 32 may be formed as a removable block 34, since, as shown, it overlaps the upper end of the head 45 sleeve 25 on the drill shank and would otherwise

interfere with the assembly or removal of the drill. Preferably, each of the bores 26 which accommodate the head sleeves 25 of the drill shanks is formed with an inclined notch 27 leading from the side of the bore opposite that at which the cam 32 is positioned, so that if the plunger 30 follows the upper end of the drill shank into the bore 26 it will ride out along the inclined surface of the notch 27 as the body 19 continues to rotate after delivery of the hammer blow of the plunger 30. It may be understood that although Figure 5 shows the plungers 30 as equal in number to the drill shanks 20, and as spaced at the same intervals so that their hammer blows will be delivered simultaneously to the drills, this arrangement is not essential; for example, four or five plungers might be provided to operate upon three uniformly spaced drills so that the hammer blows would not be simultaneously delivered, but each drill would receive four or five such blows during one rotation of the body 19 in which it is carried.

While there are shown and described herein certain specific structure embodying the invention, it will be manifest to those skilled in the art that various modifications and re-arrangements of the parts may be made without departing from the spirit and scope of the invention, and that the same is not limited to the particular form herein shown and described, except in so far as indicated by the appended claims.

I claim as my invention:

1. In a well drilling apparatus, a drill pipe, a drill bit rotatably attached to the lower end thereof, fluid motor means responsive to the flow of drilling fluid through the apparatus for rotating the bit, the drill pipe and the bit having adjacent portions with opposing transaxial faces, the said face of the bit including a plurality of projections uniformly spaced around the axis of rotation of the bit, and each formed with a sloping surface inclined toward the opposing face of the pipe and ending at an abrupt shoulder approximately perpendicular to said face, the pipe carrying a plurality of spring-pressed plun- 45

gers spaced around the axis of rotation of the bit in position to engage said projections as the bit rotates, said drill bit including a body portion and a plurality of drill points each having a shank slidably carried in said body with spring means upholding said shanks therein and with the upper end of each drill shank adjacent the abrupt shoulder of one of said projections whereby rotation of the drill bit causes the plungers to ride up the inclined faces of the projections and to be driven suddenly against the upper ends of the drill shanks as the abrupt shoulders of the projections pass under the plungers.

2. In a well drilling apparatus, a drill pipe, a drill bit rotatably carried at the lower end thereof and comprising a body portion with a plurality of drill points slidably mounted therein, the drill pipe and the bit having adjacent portions with opposing transaxial faces, means by which said drill bit is rotated relatively to the drill pipe, the said face of the bit including a plurality of projections uniformly spaced around the axis of rotation of the bit, and each formed with a sloping surface inclined toward the opposing face of the drill pipe and ending at an abrupt shoulder approximately perpendicular to said face, the drill pipe carrying a plurality of spring-pressed plungers spaced around the axis of rotation of the bit in position to engage said projections as the bit rotates, and means yieldingly upholding the shank of each drill point adjacent the abrupt shoulder of one of said projections, whereby rotation of the drill bit causes the plungers to ride up the inclined faces of the projections and to be driven suddenly against the upper ends of the drill shanks as the abrupt shoulders of the projections pass under the plunger.

3. In the combination defined in claim 2, said abrupt shoulders engaging with the respective plungers to operate as clutch means for rotating the bit bodily with the drill pipe when the latter is rotated.

JAMES W. MENHALL.
